UNITED STATES PATENT OFFICE

2,470,268

SAFETY THERMOSTATIC CONTROL FOR
GASEOUS BURNERS

Maurice Rowan, Richmond Hill, N. Y.

Application March 7, 1945, Serial No. 581,375

1 Claim. (Cl. 158—117.1)

1

This invention relates to the combination with one or more gaseous fuel burners of a thermostat arranged to be acted on by the pilot flame of the burner or burners, and having means for shutting off the flow of gas or fuel oil, which will operate when the pilot flame ceases.

One of the objects of the invention is the provision of a combined shut off valve for the fuel line and a thermostat, which will remain inoperative so long as the pilot flame is active, but which will react to close the valve when the flame is blown out, or when the flame ceases through the loss of pressure.

Another object of the invention is the provision of a thermostatically controlled shut off fuel valve, with a manually controlled by-pass, so arranged that when the valve is closed by the action of the thermostat the fuel flow may be opened to the pilot burner, until the thermostat is cooled sufficiently to resume a normal condition for operation.

With the above and other objects in view the invention comprises certain new and useful constructions, combinations and arrangements of parts, clearly described in the following specification, and fully illustrated in the accompanying drawings, in which:

Fig. 1 is a plan view, showing the invention applied to a gas burner set which includes four individual burners and a single pilot flame burner, located centrally thereof.

Fig. 2 is a sectional view, taken on line 2—2 of Fig. 1, looking in the direction of the arrows.

Referring to the accompanying drawings, which illustrate the practical embodiment of the invention, 5 designates a gas range or stove, having a plurality of individual gas burners 6, supplied through the fuel supply pipe 7, and the Bunsen-mixers 8, in the usual manner.

Gaseous fuel is supplied to the pipe 7 by the service pipe 9, in which the shut-off valve 10 is installed. This shut-off valve is provided with a valve stem 11, on which the crank arm or lever 12 is mounted, and this crank arm or lever is pivotally connected to the outer end of the thermostat rod 13, which is enclosed by the aligned tubes 14 and 15, the inner ends of which are spaced from each other by the distributor 16 of the pilot flame burner 17.

The distributor 16 of the pilot burner 17 is 50 fined by the claim hereof.

2

equipped with four distributor or flame tubes 18, which extend radially to the individual burners 6. The thermostat rod 13 engages a stop 19 in the outer end of the tube 15, which prevents endwise movement of this rod, and this stop acts as a thrust bearing for the thermostat rod, and the thermostat rod can contract or extend only in the direction of the valve.

The pilot flame of the burner 17 acts directly 10 on the thermostat rod, and normally maintains this rod expanded, and when so expanded the valve is kept open. But when the pilot flame is blown out, or the pressure drops so that the flame ceases, then the thermostat rod will contract by 15 cooling, and this cooling or contraction will close the valve, thereby shutting off the flow of gas to the pilot burner and the individual burners of the range.

The pilot flame can be projected through each 20 of the distributor tubes, so that each of the burners 6 will have its own local pilot flame.

When the thermostat rod contracts and closes the valve 10, flow to the pilot flame burner 17 may be temporarily renewed by opening the small 25 screw by-pass needle valve 19a, so as to allow gas to flow through the by-pass pipe 20 to the pipe 21 which supplies gas to the burner 17, from the valve 10.

The flow of gas to the pilot flame burner is 30 increased by the operation of the manual valve 22, which controls the flow of gas through the auxiliary supply pipe 21 from the supply pipe 7. When this pilot burner valve is opened the flame of the pilot burner is increased to such a 35 degree that flames are propagated through the distributor tubes 18 to the individual burners. The distributor 16 is provided with air intake openings 16a, so that an ample air supply will enter the distributor to support the consumption 40 required when the valve 22 is opened.

It is understood that the invention may be applied for the control of oil burners, which employ a pilot flame burner, or which can be adapted to employ such a burner.

45 It is also understood that various changes in the details of construction, their combination and arrangement may be made, and that all materials available for the construction required may be used, within the limits of the invention, as de-

Having described my invention, I claim as new:

The combination with a stove having a plurality of gaseous burners, a pilot flame igniter having a burner and distributor chamber means supporting the burner and surrounding the same, a horizontal flame ignition tube extending to each burner from said chamber means, a gas supply pipe for the pilot burner, a turn valve therefor, a pair of tubes connected with the distributor chamber means and extending from opposite sides thereof in axial alignment with each other, the outer end of one of said tubes being closed, and a thermostatic rod having an end portion engaged with the closed end of said last-named tube and extending through the opposing tube and pivotally connected with the valve, said thermostatic rod extending through the chamber means and directly over the pilot burner to be heated by the flame thereof and adapted to contract when said flame is extinguished to close the valve by such contraction, said tubes being greater in internal diameter than the diameter of the rod whereby to permit the free deflection of the rod throughout its entire length and the turning of the valve through its pivotal connec-

tion therewith, said rod being contractible from its engagement with the one tube to its connection with the turn valve.

MAURICE ROWAN.
